Patented Jan. 20, 1925.

UNITED STATES PATENT OFFICE.

LEWIS ALEXANDER, OF CLINTON, ILLINOIS.

RAIL-CROSSING CONSTRUCTION.

Application filed April 3, 1924. Serial No. 703,847.

To all whom it may concern:

Be it known that I, LEWIS ALEXANDER, a citizen of the United States, and resident of Clinton, De Witt County, Illinois, have 5 invented a certain new and useful Improvement in Rail-Crossing Construction, of which the following is a specification.

This invention relates to rail crossing devices of that kind in which means are provided for connecting the rails at right angles to each other, so that the rails of one track will in effect cross those of another track, usually at right angles to each other, or approximately so, thus providing a crossing 15 construction whereby trains on either track may cross the other track.

Generally stated, the object of the invention is to provide a novel and improved construction and arrangement whereby no 20 short rail sections will be necessary between the sides of either track, and whereby the ends of the rails of both tracks will be firmly connected and held in place by means which serve also as means, in effect, for preserving the continuity of the rails of both 25 tracks, so that the crossing construction will support the wheels between the sides of either track, in a manner that will insure rigidity and other necessary requirements 30 or desirable characteristics of a structure of this kind, and in a manner to reduce the cost of manufacture and installation of a crossing construction for this purpose.

It is also an object to provide certain 35 details and features of construction and combinations tending to increase the general efficiency and the desirability of a rail crossing of this particular character.

To the foregoing and other useful ends, 40 the invention consists in matters hereinafter set forth and claimed and shown in the accompanying drawings, in which—

Figure 1 is a plan of a rail crossing structure embodying the principles of the invention;

Figure 2 is a transverse section on line 2—2 of Fig. 1;

Figure 3 is a detail plan view of the center plate involved in said construction;

Figure 4 is a transverse section on line 4—4 of Fig. 3;

Figure 5 is a detail plan view of one of the tie plates interposed between the rails of each track, involved in said construction;

Figure 6 is an edge view of the plate shown in Fig. 5;

Figure 7 is a detail plan view of one of the angle plates disposed in the angles between the outer sides of the two tracks; and

Figure 8 is an edge view of the plate 60 shown in Fig. 7.

Figure 9 is a detail fragmentary sectional view, on a larger scale, showing the manner in which the fastening bolts are applied.

As thus illustrated, the invention comprises the rectangular center plate, as shown in Fig. 3, having four straight edge portions 1, and having inside web portions 2, provided with openings 3, for fastening bolts, as will hereinafter more fully appear. 65

The tie plates, such as the tie plate shown in Fig. 5, each have an edge portion 4 to support the wheels of the trains, and web portions 5 and 6 having holes 7 therein for bolts or other fastening devices, as will herein- 70

after more fully appear. The edge portions 8 of each tie plate are adapted to fit against the inner sides of the rails 9, as shown, and the raised portions 10 serve as guards for the flanges of the wheels of trains crossing 75

at right angles to the portion 4 of each tie plate, as will hereinafter more fully appear. Each angle plate, as shown in Fig. 7, comprises a right angled crossing portion 11 to support the wheels of trains on both tracks, and each angle plate is provided with edge 80

portions 12 to engage the sides of the rails of both tracks, these angle pieces being disposed in the angles between the outer sides 85

of the rails of the two tracks which, in the 90 illustration embodied in the invention shown in the drawings, cross each other at right angles. Each angle plate is provided with a web 13 having holes 14 for bolts or other fastening devices, as will hereinafter more 95

fully appear. The edge portions 8 and 12 have horizontal holes to receive the horizontal bolts 15, whereby the end portions of the rails are clamped tightly between these 100 portions of the plates. The end portions of the rails, as will be seen, are undercut to provide upper tread portions 16 which extend over the portions 12 to engage the portions 11, so that there is scarcely any break or gap anywhere in the tread portions over 105 which the wheels roll while crossing the construction thus provided. Of course, grooves 17 are formed between the rectangular center plate and the tie plates, for the flanges of the wheels, and extensions 18 of these grooves are formed for a distance outside of 110 the rectangular space occupied by the center

plate, between the portions 10 and the portions 11, thereby permitting the flanges of the wheels to travel across the rail crossing construction. In addition, these grooves 17 and 18 form guards for the flanges, whereby the flanges are held at both sides against lateral displacement while traversing the crossing construction. Vertical bolts 19 are inserted through the different plates, and 10 through the webs 2, 6 and 13, and through the openings 3, 7 and 14 provided therein, to clamp the different plates and the rigid structure formed by the plates in the rails upon the rectangular base plate 20, which latter may be of any suitable character. Said base plate can be supported by any suitable means, and the shape of the openings 3, 7 and 14 is such that the plates can be displaced laterally to facilitate the insertion and removal of the bolts from these holes.

Thus the eight rail end portions are rigidly connected and secured upon the base plate, thereby providing a very rigid and 25 strong construction which will withstand the vibration and shock of the passing trains. The plates between the rails of these tracks are called "tie" plates because they tie the rails together, and the plates outside 30 of the rails are called "angle" plates because they are disposed in the angles formed between the outer sides of the two tracks. Each tie plate has a portion 4 to support the wheels, and each angle plate has a portion 11 to support the wheels, these portions being of the same height as the tops of the rails, so that the wheels will travel smoothly while passing from the ends of the rails at one side to the ends of the rails at the other 35 side, of the rail crossing construction thus provided. The plates can be made of any desired material, either cast steel or wrought steel, or metal of some other kind, but it is obvious that these plates must be made of 40 such strong and tough and durable metal that they will not break or crack or bend when subjected to the weight and shock and strain of passing trains.

The construction tends to reduce the cost 50 of manufacture and the cost of installation, as compared with constructions heretofore employed for crossings of this kind.

As shown, the crossing is one in which the tracks cross each other at right angles, but 55 it will be understood that the invention is not limited to any particular angle for the crossing and that the two tracks may be disposed at any desired angle to each other, so far as the broader aspects of the invention 60 are concerned.

It will be seen that with the holes in the different plates, for the vertically disposed bolts, each bolt can be shifted sidewise, when loose or not tightened, for the reason 65 that the holes below in the base plate are

exact counterparts of the holes above in the tie plates, angle plates and the central plate. The nuts for these bolts are preferably above, and the lower portions of the bolts are squared so that they cannot turn in the 70 narrow portions of the openings in the base plate, and with this arrangement the bolts can be inserted downward through the different plates or inserted upward, and moved sidewise, which amounts to a relative lateral displacement of the plates themselves, or relative to the bolts, until the bolts themselves are in the narrow portions of the openings in the base plate and in the plates above. Then when the nuts on the outer 75 ends of the bolts are tightened, the bolts will be held against rotation by their squared portions in the base plates, whereby the tightening of the nuts will clamp the upper plates firmly upon the base plate, the upper plates and the rails forming one rigid mass or structure which is held in fixed position upon the base plate. This permits assembly 80 of the plates and removal thereof without the necessity of obtaining access below the base plate. But any suitable means can be employed, of course, for attaching the upper plates to the base plate or to any suitable support, without departing from the spirit 85 of the invention.

What I claim as my invention is:

1. In rail crossing construction, the combination of rails forming tracks crossing each other at an angle, with said rails terminating at the sides of a rectangle where the rails are omitted, and plates interposed between the rails of each track, forming continuations of said rails for the wheels to travel upon, plates disposed in the angles and between the sides of one track and the sides of the other track, together with fastening devices for connecting the rails and plates together, and instrumentalities forming a base for said plates and rail portions thus connected to form a rigid rail crossing structure.

2. A structure as specified in claim 1, in combination with a rectangular guard plate disposed within the rectangular plates formed between the edges of said first-mentioned plates, spaced a distance from said edges, thereby providing spaces for the flanges of the wheels.

3. A structure as specified in claim 1, said fastening devices comprising bolts inserted through the rail end portions, said plates having portions provided with openings for said bolts, whereby the rail end portions are clamped tightly between said portions of the plates.

4. A structure as specified in claim 1, said base comprising a rectangular plate, extending under all other plates, and bolts inserted vertically to secure the upper plates to said base-forming lower plate.

5. A structure as specified in claim 1, said instrumentalities comprising a rectangular plate, together with vertical bolts extending through this base plate and said first-mentioned plates, with openings in said first-mentioned plates to permit upward insertion of said bolts through said upper plates, in assembling the structure on said base plate, these openings permitting lateral displacement of the fastening means into a position whereby said bolts are effective to hold the upper plates firmly upon said base plate.
10. 6. A structure as specified in claim 1, in combination with a rectangular plate dis-
- posed in the rectangular space formed between said first-mentioned plates, spaced a distance from said edges, thereby providing spaces for the flanges of the wheels, and said instrumentalities comprising a base plate having upstanding bolts thereon, with openings formed in said upper plates to permit upward insertion therein of said bolts, said openings being formed to permit lateral displacement of the fastening means into a position whereby said bolts are effective to hold said upper plates in place on said base plate.

LEWIS ALEXANDER.
